UNITED STATES PATENT OFFICE.

WILLIAM C. BOSENURY, OF RICHMOND, INDIANA, ASSIGNOR TO STARR
PIANO COMPANY, OF RICHMOND, INDIANA.

MECHANISM FOR OPERATING MUFFLERS ON MUSICAL INSTRUMENTS.

SPECIFICATION forming part of Letters Patent No. 686,251, dated November 12, 1901.

Application filed April 8, 1901. Serial No. 54,707. (No model.)

To all whom it may concern:

Be it known that I, WILLIAM C. BOSENURY, a citizen of the United States, residing at Richmond, in the county of Wayne and State of Indiana, have invented new and useful Improvements in Mechanism for Operating Mufflers on Musical Instruments, of which the following is a specification.

My invention relates to improvements in mechanism for operating mufflers on musical instruments to be operated by the hand of the operator; and the objects of my improvements are, first, to provide a simple and positive mechanism to be controlled by the hand of the operator and for the purpose of operating the mufflers on pianos; second, to provide a device of the class stated with new and novel features which are herein shown and which can be easily controlled by the person using the musical instrument, and, third, to provide a new article of manufacture, a device for operating and controlling the mufflers of musical instruments, which will add to the efficiency and appearance of the musical instrument without materially increasing the cost thereof. I attain these and other objects which will appear from the mechanism illustrated in the accompanying drawings, forming a part of this specification, in which—

Figure 1 is a perspective view of the inside surface of one of the outside walls of a piano, showing my invention in perspective and by means of dotted lines the two positions my mechanism is intended to assume. Fig. 2 is a sectional detail view of a portion of my mechanism greatly enlarged. Fig. 3 is a front view of the parts of my mechanism shown in Fig. 2 and on the same scale as Fig. 2. Fig. 4 is a detail cross-section of the parts shown in Fig. 5, taken from the rear on line XX of Fig. 1. Fig. 5 is a detail sectional view of the parts shown in Fig. 4, taken on the line T T of Fig. 4.

Similar figures and letters of reference refer to similar parts throughout the several views.

Referring now to the drawings, the parts referred to by figures are the parts which I claim as new, and the parts referred to by letters are old and are shown in order to show the relative location of my improvements with reference thereto.

A represents the muffler-bar which my invention is intended to operate up and down, as shown by the dotted lines.

B represents the block placed between the outer walls of the piano and the piano-keys.

C represents the outer wall of a piano.

D represents the music-shelf of a piano.

E represents the keys of a piano.

F represents the music-desk of a piano.

21 represents an arm extending backward and upward from the side of the keys E and pivotally connected to the arm 22.

22 represents an arm pivotally secured to the side of the piano and also to 21 and 23.

23 represents an arm extending up from 22 and connected near the center of the arm 24.

24 represents an arm pivotally connected to the side of the piano and to the upper end of 23.

25 represents a spring-clamp for holding 24 in contact with the pivot 31 and the side of the piano.

26 represents a spring-clamp for holding 24 in contact with 23 and the pivot 30.

29 represents a rivet securing 26 to 23.

30 represents a rivet passing through 26, 24, and 23.

31 represents a rivet or pin uniting 24 and 25.

32 represents a screw by which 25 is secured to the piano.

33 represents a pin or rivet connecting 23 and 22.

34 represents a pin or rivet connecting 21 and 22.

35 represents a screw by which the end of 22 is fastened to the piano.

36 and 37 represent wooden pins or pegs secured in the piano and act as stops for my mechanism.

38 represents a plate with a longitudinal slot secured to the block B, as shown.

40 represents a knob attached to 21 and extending up through the slot in 38 for the purpose of forming a hold by which my mechanism can be operated by hand.

The operation of my mechanism is accomplished by moving the knob 40 backward and forward, as shown by the dotted lines, to operate the muffler. Thus it can be seen that when the knob 40 is slid to the front of the slot in the plate 38, as shown by the

solid lines in Fig. 1, my mechanism will assume the position shown by the solid lines throughout the view. Desiring now to raise the muffler A, the knob 40 is pushed to the rear in said slot, when the mechanism and the muffler will assume the position shown by the dotted lines in Fig. 1, whereupon the arm 22 will abut the stop 36, and the pivot 33 will be on a "dead-center," which insures the retention of the parts in position without the aid of a locking device until the knot 40 is pulled to original position.

My improvements are herein shown as applied to the inside left-hand end of a piano. It is apparent that they are equally applicable for attachment on the opposite end of a piano, if so desired.

From the foregoing description, taken in connection with the drawings, the operation of this invention will be readily understood and its many advantages be fully appreciated, and I will simply state that the device herein shown by reason of its simplicity, attractiveness, ease and efficiency of operation will prove a useful and practical invention, as I have fully demonstrated.

My improvements are perfectly adapted to accomplish the results for which they are intended; but it is evident that changes in and modifications of the construction herein shown and described may be made and that analogous parts may be used to accomplish the same results without departing from the spirit of my invention or sacrificing any of its many advantages.

Having shown and described the best construction of my improvements to me known at this time, what I claim as new, and desire to secure by Letters Patent of the United States, is—

1. In a mechanism for operating muffler-bars of pianos, the combination with a muffler-bar, of a pivoted arm connected thereto, a second pivoted arm, stop-pins on opposite sides of the second pivoted arm and limiting the movement of said arm, a connecting-arm

extending between said arms and pivotally connected to both of them, a substantially horizontally movable arm pivoted to the arm playing between the stops, and a handle for the horizontal arm, one of said stop-pins being adapted to arrest the play of the second arm to cause its pivotal connection with the connecting-arm to lie on a dead-center and hold the muffler-bar in operative position. 55

2. In a mechanism for operating muffler-bars of pianos, the combination with a muffler-bar, of an arm having one end connected thereto and pivoted at its other end, a connecting-arm pivoted to the aforesaid arm intermediate the length thereof, separate stop-pins, a lever having one end pivoted to the piano and its other end pivoted to the end of the connecting-arm, and adapted to play between the stop-pins, a substantially horizontally movable arm pivoted to the lever intermediate the ends thereof, and a handle for the horizontal arm, one of said stop-pins being adapted to arrest the play of the lever to cause its pivotal connection with the connecting-arm to lie on a dead-center and hold the muffler-bar in operative position. 65

3. In a mechanism for operating muffler-bars for pianos, the combination with a muffler-bar, of an arm connected to the muffler-bar and being itself pivoted, a connecting-arm, a spring plate or clamp having one end secured to the connecting-arm and its other end free to spring toward and away therefrom, said muffler-operating arm being located between the spring-clamp and the operating-arm and having a pin whose ends project into apertures in the spring and connecting-arm. 75

In testimony whereof I have signed my name to this specification in the presence of two subscribing witnesses.

WILLIAM C. BOSENBURY.
